TYING DEVICE

Robert A. Harschnek, Chicago, Ill., assignor to
 Industrial Patents Corporation, Chicago, Ill., a
 corporation of Delaware

Application December 17, 1936, Serial No. 116,405

2 Claims. (Cl. 226—129)

This invention relates to a method of measuring and cutting tie strings and means therefor.

One of the objects of the invention is to provide an improved tying device.

5 Another object of the invention is to provide an improved means for measuring and cutting tie strings.

Another object of the invention is to provide a novel method of measuring and cutting tie 10 strings.

Other objects of the invention will be apparent from the description and claims which follow.

In the drawings like characters of reference are used to designate similar elements in the several figures.

Figure 1 is a plan view of a device constructed in accordance with the present invention.

Figure 2 is a front view of the device shown in Figure 1.

20 Figure 3 is an end view of the device shown in Figure 1.

Figure 4 is a side view of one of the cutter blade holding elements utilized with the device of the present invention.

25 Figure 5 is a side view of another of the cutter blade holding elements.

Figure 6 is a side view of the string holding spring associated with the cutter.

Figure 7 is an end view of the spring element 30 shown in Figure 6.

Figure 8 is a perspective view illustrating the manner of using the device shown in Figure 1.

The tying device, illustrated in the drawings, comprises a base 1, of metal or other suitable material cut and bent to provide front wall 2, rear wall 3, end walls 4 and 5 and flanged end members 6 and 7, the flanged end members 6 and 7 being provided with suitable openings 8 for rigidly securing the device to a table or other 40 supporting means as by screws or the like.

String holder and guide bracket 9 is rigidly secured, as by bolts 10, to rear wall 3 and is provided with a series of openings 11 through which is threaded string 12 extending from a ball, not 45 shown, in the manner illustrated in Figure 8, offering resistance to paying off string from the ball.

Tying and measuring post 13, slotted at one end, as at 14, is rigidly secured, as by nuts 15, 50 in one of several openings 16 in flange member 7. Tying post 13 may be secured in any one of the openings 16 for suitably measuring a looped length of string 17 relative to fixed cutter 18, in the manner shown in Figure 8.

55 Cutter 18 comprises members 19 and 20 se-

cured one against the other, as by screws 21, passing through openings 22 and thus serve to rigidly secure blade 23 on pins 24 formed integral with member 19.

It will be noted that each of the members 19 and 20 are suitably slotted, as at 25, and that cutting edge 26 of blade 23 is fixedly mounted so as to diagonally intersect the slots 25 thus forming cutting throat 27.

Spring member 28 serves to retain the loose end of string 12 after each cutting operation. Spring member 28 is rigidly secured adjacent member 20 and comprises plate 29 provided with relatively wide edge 30 against which flat arm 31 of spring 32 is constantly urged. Spring 32 is 15 formed as shown in Figure 6 and is rigidly secured to plate 29, as by screw 33. Plate 29 is rigidly secured against member 20 with edge 30 in alignment with cutting throat 27.

In practicing the method of the present invention, the free end of the main strand of string 35 is drawn past cutter 18 to and around guide post 13 and back to cutter 18 in the form of a measured loop of string 17, whence the measured loop of string 17 is severed from the main strand 25 of string.

It will be seen that the severed loop of string 17 will be retained on post 13 with the two ends thereof brought together, for tying, for example, 30 casing 34.

In the method of tying casing 34, which does not form part of the present invention, the casing 34 is left hanging from post 13 by loop portion 36 of the loop of string 17. The cutter 31, rigidly secured to wall 2 as by screws 38, may be used 35 for severing the surplus ends of the string after tying of the casing 34.

Collecting strand 39 is secured in slot 14 in the manner shown in Figure 8 for tying together a hank of casings 34 through loop portions 36. 40

I claim:

1. A string measuring, cutting and tying device comprising a base, a string holder and guide member secured to the base, a tying and measuring post secured to the base in fixed spaced relationship with the string holder and guide member, and a cutter secured to the base intermediate the string holder and guide member and the tying and measuring post, the string holder and guide member, the measuring and tying post and the cutter being secured one relative to the other in a substantially straight line whereby a main strand of string may be drawn from the string holder and guide member to and around the string tying and measuring post and back to the cutter to form 45 50 55

a measured loop of string, and whereby the measured loop of string may be severed from the main strand of string with the two ends of the measured loop of string brought together for tying.

5 2. The method of measuring and cutting tie strings which comprises drawing the free end of a main strand of string from a supply past a cutting point to and around a support spaced from the cutting point half of the distance of the de-

sired length of string, continuing to draw the free end of the main strand of string drawn to and around the support back to the cutting point in the form of a measured loop and severing the main strand of string at the cutting point whereby 5 the two ends of the measured loop of string are brought together for tying and the measured loop of string is retained by the support.

ROBERT A. HARSCHNEK.
